[57] ABSTRACT

Apparatus for packaging tea bags distended in part by a non-uniform distribution of tea therein, comprising a rotor on which there is mounted a carton holder for movement from a loading station at which it is adapted to receive and support a carton in an upright position with its upper end open and with a stack of tea bags therein, the collective thickness of which exceeds the depth of the carton with the excess tea bags supported above the open end; to a second station where the carton is vibrated to effect a redistribution of the tea in the tea bags such as to diminish the height of the stack to a dimension no greater than the depth of the carton and where the carton is partially closed; and from thence to a third station where the filled carton is discharged and simultaneously completely closed.

SEMI-AUTOMATIC MACHINE FOR PACKAGING TEA BAGS

BACKGROUND OF THE INVENTION

According to current practice packets of tea, sugar, catsup and the like for individual use are made by feeding a continuous strip of suitable sheet material folded longitudinally first to a side sealer which seals the folded strip at intervals corresponding to the desired packet size; from thence to a filling device for filling the pockets formed thereby; from thence to a top sealing device for closing the open tops; and finally to a cutting device for cutting the strip of packets into individual packets. The individual packets are then manually deposited in the right number in cartons of suitable size for distribution and sale. To facilitate deposition the packets in cartons they may be oriented by means of the apparatus disclosed in U. S. Pat. No. 3,747,737 to dispose them in face-to-face relation so that the required number of packets may be removed as a group or groups from a single or double columns of packets. Throughout the processing as described the packets are supported at their tops so that the material deposited in the packets settles to the bottom portions of the packets, distending the lower portions of the packets. The upper portions of the packets in contrast are only as thick as the two thicknesses of the material of the packets. It is evident therefore that when a group of packets are placed in a carton of predetermined depth only as many may be inserted as correspond in collective thickness to the depth of the carton and that because of the non-uniform thickness of the packets, thick in part and thin in part, the packets will slump down at the thin side. Subsequent handling of the cartons following filling as, for example, shipping and unpacking for display purposes, will effect a certain amount of redistribution of the content of the packets within the cartons so that they will occupy much less than the entire interior volume of the cartons with the result that when the customer purchases a carton and opens it he will find it only partially filled and with the packets in disarray. To avoid the foregoing it is customary to fill the cartons with as many as will fit into them without applying pressure; then to shake the cartons until the packets settle down; then to add a few more packets and again shake the cartons; and so on until the required number of packets are contained within the cartons and such that further agitation of the cartons will not cause further diminution. The apparatus of this invention is designed to automatically load cartons with a sufficient number of packets to entirely fill it and in such a state of uniform distribution of the material within the packets that the packets will be orderly disposed therein and will completely fill the cartons.

SUMMARY

As herein illustrated, the apparatus comprises a movable support, a carton holder mounted on the movable support, a plurality of spaced operating stations at which operations are performed in succession which contribute to filling and closing the carton, means for effecting intermittent movement of the movable support and hence the carton holder from station to station, a first station, a stationary support at said first station to which packets are delivered, said carton holder when at said stationary support being adapted to re-

ceive and support a carton in an upright position with its upper end open and with a stack of packets therein comprised of a predetermined number of packets, the collective thickness of which exceeds the depth of the 5 carton with the excess packets above the open end, a second station, means at the second station operable to reduce the collective thickness of the packets to a dimension not exceeding the depth of the carton and to partially close the open end of the carton, a third station, and means at the third station operable to discharge the filled carton and simultaneously to completely close the carton. The carton holder embodies a portion which provides an extension at the open end of the carton, corresponding substantially in cross-section 10 to the interior of the carton and of sufficient length such as to accommodate the excess number of packets. The stationary support is adapted to support the carton on its side with its open end in a position adjacent the place of delivery of the packets thereto and there is 15 means supporting the carton holder on the movable support for movement from an upright position to a prone position over the carton resting on the stationary support with said portion extending beyond the open end of the carton in a position for receiving and guiding the packets into the open end of the carton. There is 20 latch means on the carton holder movable into engagement with the carton as the carton holder is moved to said prone position to engage and hold the carton within the holder as the latter is moved to its upright position and there is means on the movable support for 25 latching the holder in its upright position. A gauge block on the stationary support provides for locating the carton in the proper position for engagement of the carton holder therewith. There is means for effecting 30 intermittent movement of the movable support to move the work holder from the first station to the second station and there is means at the second station for effecting vibration of the carton while supported by the work holder until the entire stack of packets diminishes in 35 thickness to a dimension not greater than the depth of the carton. At this station there are folding devices for closing the dust flaps of the carton and holding them closed while the carton is moved by the carton holder to the third station where there is a ram for effecting 40 ejection of the filled carton from the carton holder and a folding device for folding the closure flap over the dust flaps. Optionally there is a fourth station where there is means for restoring the folding devices which 45 are moved into operative position at the second station and were maintained in their operative position while the carton was moved from the second station to the 50 third station to their inoperative position preparatory to movement of the carton holder to the first position for the next cycle of operation.

55 The invention will now be described in greater detail with reference to the accompanying drawings wherein:

60 FIG. 1 is a plan view of the apparatus herein illustrated showing conveyor means for delivering tea bags thereto;

65 FIG. 2 is an elevation with parts in section looking in the direction of the arrow 2-2 of FIG. 1;

FIG. 3 is an elevation, to much larger scale, partly in section, showing the support for the rotor;

FIG. 4 is an elevation taken on the line 4-4 of FIG. 1;

FIG. 4a is a perspective view of a pilot member;

FIG. 4b is a fragmentary section of the back part of the carton holder provided with clusters of bristles for supporting the upper ends of tea bags upright;

FIG. 5 is a section taken on the line 5—5 of FIG. 4;

FIG. 6 is an elevation, to much larger scale, of a carton holder for a carton adapted to hold 48 tea bags;

FIG. 7 is a rear view of the carton holder shown in FIG. 6;

FIG. 8 is an elevation of a carton holder adapted to hold a carton for receiving 100 tea bags;

FIG. 9 is a front view of the carton holder shown in FIG. 8;

FIG. 10 is an enlarged section taken on the line 10—10 of FIG. 7;

FIG. 11 is a plan view with the rotor omitted showing the path of travel of the carton holder from station A to station B and from thence to station C, showing at station C part of the discharge mechanism at that station;

FIG. 12 is an elevation, to large scale, showing the latch means for holding the carton holders in their upright positions;

FIG. 13 is a plan view, to larger scale, of the mechanism at station B for effecting vibration and partial closure of the carton;

FIG. 14 is an elevation, to larger scale, taken on the line 14—14 of FIG. 2 showing the mechanism for lowering the carton support at station B;

FIG. 15 is a view taken in the direction of the arrows 15—15 of the mechanism shown in FIG. 14;

FIG. 16 is an elevation taken on the line 16—16 of FIG. 2;

FIG. 17 is an elevation taken on the line 17—17 of FIG. 16;

FIG. 18 is an elevation, to larger scale, taken at station C in the direction of the arrows 18—18 of FIG. 11;

FIG. 19 is an elevation taken on the line 19—19 of FIG. 18;

FIG. 20 is a plan view taken on the line 20—20 of FIG. 18;

FIG. 21 is an elevation taken on the line 21—21 of FIG. 20;

FIG. 22 is an elevation taken on the line 22—22 of FIG. 1;

FIG. 23 is an elevation taken on the line 23—23 of FIG. 22;

FIG. 24 is a fragmentary elevation of the vibrating mechanism; and

FIG. 25 is a plan view taken on the line 25—25 of FIG. 2.

Referring to the drawing (FIG. 1), the packaging apparatus herein shown comprises a rotor 10 on which there are mounted at equal angular distances from each other carton holders 12 for movement about a vertical axis relative to correspondingly angularly spaced stations A, B, C and D situated about the axis of rotation to which the carton holders are moved successively. At station A a predetermined number of packets in excess of the number the carton will hold without redistribution of their contents to make them substantially uniformly thick are supported in the carton; at station B the contents of the packets are redistributed so that the entire number of packets are contained by the carton and the carton is partially closed; at station C the carton is discharged and completely closed; and at station

D the carton holder is made ready for the next cycle of operation that commences at station A.

Referring to FIG. 2, the rotor 10 is mounted on a base 14 which comprises a rigid, horizontally disposed table member 16 supported along its opposite sides by leg members 18—18 which provide at the underside of the table member 16 an enclosure and support for the drive means which controls and effects operation of the several functions which contribute to the packaging operation.

The rotor 10 comprises a circular plate 20 (FIG. 3) fastened by bolts 22 to a hub member 24, the latter being mounted on the upper end of a vertically disposed indexing shaft 26 journaled in bearing members 28—28 which are supported in a hollow column 30, the lower end of which is provided with a base flange 32 by means of which it is bolted in an upright position to the table member over an opening 34 therein, through which the index shaft 26 extends to the lower side of the table member for connection with the drive means which will be described hereinafter. The circular plate 20 has peripherally thereof a downwardly extending annular rim 36 and there are four radially extending arm assemblies 38 fastened thereto at equal quarter circular positions around the rim by means of bolts 40. Each arm assembly FIG. 1 has a pair of arms comprising divergent portions 42—42 and parallel portions 44—44. The divergent portions of the arms of the respective assemblies are substantially parallel with those of the adjacent assemblies. Between the distal ends of the parallel portions 44—44 of each arm assembly there is mounted a carton holder 12, — the carton holder herein illustrated being designed to hold cartons for 48 and 100 tea bags respectively.

Referring to FIGS. 6 and 7, the carton holder for a carton which will hold 48 tea bags comprises a support 50 for receiving and holding a carton and a guide 52 for guiding packets into the carton held in the support and for holding packets in excess of the number of packets which will fit into the carton before redistribution of their contents at the open end thereof. The support 50 comprises a back part 54 and forwardly extending spaced parallel side parts 56—56. The holder is open at the front and the distance between the side parts 56—56 corresponds to the width of the carton to be supported thereby so that the carton may be introduced through the open front into the holder between the side parts. The forward edges of the side parts 56—56 have divergent lips 58—58 to facilitate entry of the carton through the front opening. In order to hold the carton in place there are latched members fastened to the side parts, each comprising a flat flexible blade 60 bolted to the side part with one end extending beyond the forward edge thereof. Latch blocks 62—62 are secured to the confronting sides of the blades and extend inwardly from opposite sides toward each other so that the space between them is less than the width of the carton to be introduced into the holder. The outer sides of the blocks 62—62 have divergent surfaces 64—64 to facilitate displacement of the latch members as the carton is introduced into the holder and at their inner sides shoulders 66—66 which, by engagement with the carton after it is introduced into the holder, retains the carton in place. For mounting the holder between the parallel portions 44—44 of each arm assembly there are secured to the side parts

56—56 trunnion supporting blocks 68—68 to which trunnions 70—70 are attached.

The back part 54 of the support 50 extends upwardly beyond the side parts 56—56 and the guide 52 is mounted on this upwardly extending portion of the back part in longitudinally spaced relation to the support 50 and comprises forwardly extending, spaced parallel side walls 72—72 and a front wall 74 which, together with the back part 54, constitutes a rectangular structure, the interior of which corresponds to the cross-section of the carton and provides a guide passage through which packets are adapted to be guided into the open end of the carton mounted in the support.

The cartons which are to be filled are of the kind having dust flaps at their opposite ends and a closure flap along one side and when a carton is mounted in the support the dust flaps and closure flap must be held in their open extended positions to permit the packets to be introduced through the open end of the carton. In order to hold these flaps in their open positions the distance between the lower edges 76—76 of the side walls 72—72 and the lower end of the holder is made less than the height of the carton plus the length of the dust flaps so that when a carton is mounted in the support the lower edges of the side walls 72—72 will enter between the dust flaps and hold them spread apart as shown in dotted lines in FIG. 6 and the distance between the lower edge 78 of the front wall 74 which extends downwardly beyond the lower edges 76—76 of the side walls is made less than the height of the carton plus the length of the closure flap so that the lower edge of the front wall 74 will engage the inner side of the closure flap.

The cartons are designed to receive two columns of tea bags; hence a divider 86 FIGS. 6 and 10 is mounted on the back part 54 within the guide midway between the side walls 72—72 so as to extend forwardly between the side walls and divide the guide passageway into two parts for receiving two columns of packets and guiding them in parallel relation to the carton. The divider extends longitudinally from the guide passage to approximately the open end of the carton situated in the support and is secured to the back part as shown in FIG. 10 by screw bolts 87 which extend through attaching flanges 90—90, the back part 54 and into a reinforcing plate 92 bolted to the outer side of the pack part. The attaching flanges 90—90 extend laterally of the divider and have at their extremities forwardly extending serrated edges 94—94 which are located substantially midway between the divider and the opposite side walls 72—72 at each side. The forwardly projecting serrated edges 94—94 serve to prevent the packets from tipping over as they are guided into the carton as will appear hereinafter.

At the upper ends of the side parts 56—56 there are mounted in the spaces between their upper ends and the lower edges 76—76 of the side walls 72—72 closure assemblies 96—96 comprising pivotally supported closure plates 98—98 mounted on shafts 100—100 journaled in bearing members 102—102 which are fastened to the side parts 56—56 by screw bolts 103. The axis of the shafts 100—100 are parallel to the ends of the carton so that the closure plates 98—98 when rotated inwardly about their axes will fold the dust flaps of the carton inwardly over the open end.

There is mechanism operable to rotate the closure plates 98—98 at an appropriate time comprising crank members 104—104 mounted on rearwardly extending portions of the shafts 100—100 provided with angularly disposed arms 106—106 and 108—108 as shown in FIG. 7, the arms being disposed in a plane parallel to the back part 54. The arms 106—106 have at their ends pins 110—110 on which there are mounted cam rollers 112—112 and the arms 108—108 have at their ends pins 114—114. Coiled springs 116—116 are secured at one end to the pins 114—114 and at their opposite ends to pins 118—118 secured to the back part which yieldably bias the cranks in directions to hold adjustably mounted stop screws 117—117 threaded into the lower ends of the closure plates 98—98 against the side parts 56—56, in which position as shown in FIG. 7 the closure plates 98—98 are held away from the opposite sides of the holder in their inoperative positions. Rotation of the cranks by downward displacement of the cam rollers 112—112 will rotate the closure plates inwardly from opposite sides through the openings into engagement with the dust flaps and fold the latter over the open end of the carton.

The carton holders, as described above, are pivotally mounted at their lower ends by means of the trunnions 70—70 between the lower ends of the parallel portions 44—44 of the arm assembly in upright positions so that as each holder is moved to the station A it can be rotated from its upright position downwardly into engagement with a carton resting in a prone position at the loading station. Pivotal movement is effected manually and for this purpose there is provided a handle 120 which is affixed to a block 122 fastened by screw bolts 124 to one of the side walls 72, the right side as shown in FIG. 7.

The carton holders adapted to receive 100 tea bags are shown in FIGS. 8 and 9, and the primary difference between these carton holders and those shown in FIGS. 6 and 7 is in their greater lengthwise dimension for accommodating cartons which are longer from bottom to top. In these figures the parts corresponding to those described in FIGS. 6 and 7 are correspondingly numbered with the exponent x. Because of the length of the side parts 56x—56x there are two sets of divergent lips 58x—58x at the forward edges of the side parts 56x—56x to facilitate guiding the carton into the holder.

Each of the carton holders is held in its upright position by a latch 126 mounted on one of the arm portions 44. Referring specifically to FIG. 12 the latch comprises a rigid arm 128 fixed to a rocker 130 which is pivotally mounted on a pin 132 secured to a post 134 bolted to the upper side of the arm portion 44 by a bracket plate 136. The arm 128 contains a notch 138 which is adapted to engage the handle 120, 120x. A coiled spring 140 mounted on the pin 132 with one end 142 anchored in the bracket plate 136 and the other end 144 bearing against the rocker 130 urges the arm in a counterclockwise direction as seen in FIG. 12, so as to hold the notched arm 128 engaged with the handle 120, 120x. The distal end 146 of the arm provides a finger hold which may be grasped to disengage the arm from the handle to allow the holder to be rotated from its vertical position to a horizontal position. When the holder is returned to its upright position the handle becomes automatically engaged with the arm and will

maintain the carton holder in upright position throughout the remainder of the packaging operation.

At the place of loading A (FIG. 1), that is, where the teab bags are inserted into the carton there is a bridge structure 156 which extends from the top of the table 16 (FIGS. 4 and 5) to the discharge end of conveyor means 158 of the apparatus disclosed in U. S. Pat. No. 3,747,737 from which the tea bags are discharged in two columns in face-to-face relation in each column. On the conveyor means 158 the bags rest on edge, that is, with their lower ends which are thicker than their upper ends resting on the conveyor means and there are dividers 160 FIG. 1 on the conveyor means which separate the respective columns into groups of predetermined numbers of tea bags, for example, groups of 48 and 100. There is also a divider 162 situated on the conveyor means between the two columns so as to maintain the two columns separated from each other.

The bridge structure 156 FIG. 4 comprises a substantially rectangular frame, one end 161 of which rests on the table 16 and the other end 163 of which is secured to the discharge end of the conveyor means 158 of the aforesaid apparatus. The bridge structure has mounted on its upper side in longitudinally spaced relation on suitable spacers 164 flat plates 166 and 168, the upper surfaces of which are located in the same plane as the upper surface of the conveyor means. There is a gap between the plates 166 and 168 providing an opening 169 through the bridge member and below this opening there is mounted a funnel member 170, the purpose of which is to return tea bags to a receptacle for recovery in the event that they are discharged by the conveyor means and there is no carton in position for receiving them. The plate 166 provides a flat support for receiving the carton in a prone position, the carton being placed in this position while the carton holder is in its vertical position. In order to position the carton lengthwise with respect to the holder there is provided a gauge bracket 172 which has an upwardly projecting flange 174 against which the bottom of the carton is brought to bear when the carton is placed on the plate 166. The plate 168 has at its rear edge a depressed ledge 176 which is adapted to receive and support the upper end of the carton holder when the latter is moved to its prone position with the front wall 74 or 74x flush with the surface of the plate 168.

In order to guide the tea bags from the discharge end of the conveyor means across the plate 168 to the entrance end of the carton holder there are provided spaced parallel guide plates 178—178.

As thus constructed, the operator places a carton C (FIG. 4) in a prone position on the plate 166 with its closed bottom end engaged with the flange 174 and with its closure flap 180 extending from the bottom wall of the carton and its dust flaps 182—182 extending from the side walls of the carton whereupon he disengages the carton holder from the latch and rotates it downwardly over the carton. Such rotation brings the open side of the carton holder downwardly over the carton, the latter deflecting the latch blocks as the carton enters the holder between the side parts 56—56. As the holder is rotated further downwardly the carton is forced into the holder and the latch blocks close against the outer side of the carton so as to hold it in place. The lower portion of the front wall of the guide which is tapered at its opposite edges enters between

the dust flaps, pushing them away from each other so as to allow the side walls 72—72 to enter between the dust flaps and thus hold them spaced apart and finally as the carton holder reaches its horizontal position the front wall 74, by engagement with the closure flap, depresses it below the supporting plate 166. In this prone position of the carton holder the side walls 72—72 and front wall 74 of the guide provide a guide passage and apron from the plate 168 into the open end of the carton through which the tea bags are adapted to be pushed by the operator. In order to hold the tea bags upright and properly divided into two columns while they are being moved from the conveyor means through the guiding portion of the carton holder into the open end of the carton a pilot member 183 is employed such as shown in FIG. 4a made, for example, of a piece of cardboard folded to provide a stem 185, at one end of which there are laterally, oppositely extending flanges 184—184. As the tea bags come off of the conveyor means the pilot member 183 is placed on the surface of the plate 168 with the stem 185 between the two columns and the leading tea bags against the flanges 187—187 which thus hold them on edge whereupon the operator moves the two columns of bags supported by the pilot forwardly through the guide passage into the carton. As the tea bags are manually moved from the discharge end of the conveyor into the open end of the guide passage and into the carton the divider 86 projecting downwardly from the back part 54 enters 30 between the two columns and holds them separated. At the same time the serrations 94 by engagement with the upper ends of the tea bags prevent them from tipping over.

In lieu of the serration 94 clusters of bristles 186 may be fastened to the back part 54 so as to extend downwardly therefrom as shown, for example, in FIG. 4b. These bristles may be comprised of natural or man-made fibers such as are commonly used in brushes and are flexible enough to permit the bags to be moved into the carton without excessive resistance and yet stiff enough to provide the necessary support for the thin upper edges of the bags to prevent them from tipping over.

The conveyor means mentioned above is constructed so as to deliver the tea bags in two columns or optionally in a single column. Accordingly, if it is desirable to fill cartons designed to receive a single column of tea bags the apparatus may be easily converted for this purpose by substituting for the carton holders illustrated herein holders designed to hold such a carton. In this event the holder will correspond substantially to the holders described above except that the divider will be omitted.

It has been mentioned that the tea bags are thicker at their bottom portions than at their top portions, — this being the result of handling during the filling operations, sealing operations and orienting operations which precede the packaging due to the fact that the tea settles to the lower portions of the bags so that the lower portions are thicker than the upper portions. It is undesirable to use a carton of a bottom to top depth which corresponds to the collective thickness of the thicker portions of the bags because after packaging, handling such as shipping and stocking of shelves in retail stores will bring about a more uniform distribution of the tea in the packages so that their thickness will gradually become more uniform and when the cus-

tomer opens the package it will seem as though he has purchased an incompletely filled carton of tea bags. The apparatus of this invention is designed to overcome this undesirable condition and this is achieved by constructing the guiding portions of the carton holder long enough so that the maximum number of tea bags to be packaged may be pushed into the carton and the guide portions which constitutes an extension of the carton so that when the carton holder is erected to its vertical position the excess number of tea bags which, because of their distended condition, will not enter the carton, will be held in alignment with the open top of the carton and the latter can then be vibrated to cause redistribution of the tea in these bags until the entire number of tea bags settle into the carton.

Vibration of the carton is effected at the second station B by vibrator means which will now be described. As the rotor moves the carton holder with a carton therein toward the vibrator station the lower closed end of the carton is supported for sliding movement along the upper edge of a track 189 (FIGS. 1 and 11) concentric with the center of rotation of the rotor, the upper edge of which is at the same level as the upper edge of the flange 174 so that the carton moves smoothly from the upper edge of the flange 174 onto the tracks 189. There is a gap in the track 189 at the vibrating station B to enable bringing the lower end of the carton into engagement with a vibrator member, the track however continuing from the station B to the discharge station C for again supporting the carton as it is moved from the station B to the discharge station C.

Referring now to FIG. 2, there is at station B in the aforesaid gap a support 188 which is fixed to the distal end of an arm 190, the proximal end of which is mounted on a shaft 192. The shaft 192 has fixed to it an arm 194, the distal end of which has connected to it a connecting rod 196 which extends downwardly through an opening 198 in the table and is pivotally connected by a pin 200 FIG. 14 to one arm 202 of a crank 204. The crank 204 is pivotally mounted on a pin 206, fixed to a hanger 208 at the underside of the table and has an arm 210 which extends downwardly from its pivot on which there is mounted a cam roller 214 which is held engaged with a cam 216 fastened to a shaft 220 comprising the drive shaft. A coiled spring 222 connected at one end to a hook 224 fixed to the end of the arm 202 and at its other end to a hook 226 secured to the hanger 208 holds the cam follower 214 engaged with the cam 216. The cam 216 is so shaped that rotation of the cam about the shaft 220 will raise and lower the rod 196. The rod and hence the support 188 are normally supported in an elevated position by the cam and when the rotor moves the carton holder with the carton in it from the loading station to the station B the cam is actuated to allow the spring 222 to draw the rod downwardly and thereby to lower the support 188 away from the underside of the carton so that the carton is allowed to move downwardly into engagement with means for effecting its vibration.

The means for effecting vibration (FIGS. 1 and 24) comprises a post 227 which extends upwardly from the underside of the table through an opening 228, at the upper end of which there is a flat head 230 for engagement with the bottom side of the carton. The lower end of the post is secured to a block 231 supported between a pair of leaf spring blades 232-232, the latter in turn being fastened to a block 234 extending downwardly

from the underside of the table. The block 232 is thus supported in cantilever fashion so that it is free to move upwardly and downwardly at the ends of the spring support and vibration is imparted thereto and to the post 227 by a roller 238 mounted on its underside and a tooth wheel 240 mounted on a shaft 242 for rotation relative to the roller 238. The shaft has secured to it a sheave 244 which is driven by means of a belt 246 from a sheave 248. Rotation of the tooth wheel 240 by engagement of the teeth 250 on its surface imparts vibration to the block 231 and hence through the post 227 to the bottom of the carton. The vibration thus imparted to the carton effects a redistribution of the tea in the tea bag and vibration is continued for a length of time such as to cause the tea bags to settle wholly into the carton. To assist in the redistribution of the tea within the bag it is desirable to apply a light pressure to the uppermost of the tea bags. Accordingly, there are provided pressure-applying plates 254-254 (FIG. 2 and 13) which are supported above the carton holder at the vibrating station at the lower ends of spindles 256-256. The spindles are supported for vertical movement in bearings 258-258 mounted on an arm 260 which is in turn fastened to a stanchion 262, the lower end of which is bolted to the top of the table. A rod 264 is mounted on the stanchion is vertically spaced bearings 266-266 fastened to the stanchion and the upper end of this rod is connected to the spindles 256-256 by a forked arm 268. The lower end of the rod 264 is pivotally connected by a coupling member 270 to a link 272 and this is in turn pivotally connected to one end of a lever 274, the opposite end of which is pivotally mounted on a shaft 276 supported by a bracket member 278. Angular movement of the arm 274 about the axis of the shaft 276 will raise and lower the spindles 256-256 and thus enable raising and lowering the pressure plates 254-254 relative to the top of the carton holder. Angular movement of the arm 274 to effect lowering the pressure plates 254-254 when the carton holder arrives at the vibrating station to apply pressure to the topmost tea bags and after vibration to raise them therefrom will be described hereinafter.

Following vibration and prior to moving the carton around to the discharge station C the dust flap closure plates are rotated inwardly through the openings in the side of the carton holder to fold the dust flaps downwardly over the open top of the carton. This, of course, is effected immediately after the presser plates 254-254 are raised away from the uppermost tea bags.

The linkage for moving the dust flap closure plates into and out of operative position at station B is disclosed in FIGS. 16 and 17. When the carton holder is moved to the station B the dust flap closure plates are in their retracted positions and the cam rollers 112-112 or 112x-12x in their elevated positions as shown in FIGS. 7 and 9. Depression of these cam rollers 112-112 or 112x-12x is necessary to effect folding of the dust flaps over the open top of the carton and this folding movement is effected by a bar 280 which is fastened to a block 282 mounted at the lower end of a rod 284 extending from the lower end of a cylinder 286. The cylinder 286 FIG. 2 is mounted in a vertical position on a post 288 which in turn is mounted on a plate 289 bolted between the forward ends of a pair of spaced parallel arms 290-290, the opposite ends of

which are bolted to the stanchion 262. A guide plate 292 is bolted to the lower end of the cylinder and contains a hole 294 through which there is mounted a guide rod 296, the lower end of which is fixed to the block 282 and the upper end of which is connected to a switch 298. The guide rod 296 prevents the bar 280 from turning about the axis of the rod 284 and initiates operation of a timing device for preventing the rotor from indexing if the bar 280 fails to be withdrawn.

As illustrated in FIGS. 7 and 9, the spring members 116—116 or 116x—116x connected to the bell cranks 104—104 or 104x—104x yieldably hold the bell cranks in either of their extreme positions and so following depression of the cam rollers 112—112 or 112x—112x and rotation of the closure plates 98—98 or 98x—98x into operative position the bar 280 is elevated, leaving the closure plates in their operative positions.

The rotor is now indexed through another quarter turn to move the carton holder to the station C for discharge of the filled carton and for simultaneously folding the closure flap into engagement with the open top of the carton. As previously related, at the end of the vibration the support 188 is elevated to lift the carton off the vibrator to the level of the track so that as the rotor moves through the next quarter turn to the place of discharge the carton rests on the track and slides along it. At the discharge station C (FIGS. 1, 18 and 19), there is an upstanding frame 300 comprising spaced parallel supporting members 302—302 fastened by flange members 304—304 at their lower ends to the table 16 on which are mounted vertically spaced pairs of guide rods 306—306 at a transverse spacing corresponding to the width of the carton for guiding the carton as it is discharged from the carton holder onto a conventional discharge conveyor having a horizontal run a portion of which is shown in FIG. 20. The frame has intermediate the supporting members 302—302 bottom supporting rods 308—308 which are supported in spaced parallel relation above the table by bracket members 310 and 312. The frame has mounted at the top a closure flap folder 314 which is inclined so that as the carton is moved outwardly from the carton holder through the guides the folder will press the closure flap downwardly into engagement with the open top of the carton. The folder is secured to a bracket 316 which is adjustably mounted to the frame by means of slots 318 and screw bolts 320 so that its heightwise position may be adjusted. The folder 314 at the top is for cartons which are of a size to receive 100 tea bags. An additional folder 315 is mounted by means of a bracket 317 lower down on the frame for folding the closure flaps at the tops of cartons which are of a size to receive 48 tea bags. This folder is also adjustable heightwise by means of slots 319 and bolts 321.

The rods 308—308 as illustrated in FIG. 19 extend rearwardly at a level corresponding to the upper edge of the track 189 so that when the carton is moved to the discharge position it will rest partly on the track 189 and partly on the rods 308—308. Discharge of the carton from the carton holder is effected by means of a pusher 307 (FIGS. 18, 19, 20 and 21) which is mounted in a vertical position for movement radially with respect to the center of rotation of the rotor through the guide frame 300 to push the carton from the carton holder. Referring to FIGS. 20 and 21 there is shown a track 336 fastened to the table below the rods 308—308 in which there is mounted for sliding

movement beneath spaced parallel gibs 309—309 a slide plate 311. The rear end of the slide plate is pivotally connected to one end of a link 323. The other end of the link 323 is connected by a stud 322 to a link 324, the opposite end of which is connected to the upper end of a shaft 326 which extends downwardly through a suitable bearing and through the table. A lever arm 328 is connected at one end to the lower end of a shaft 326 and at its other end to a link 331 by a pin 330. The pusher 307 is secured to the slide plate in a vertical position by means of an angle 337 and is adapted to be moved forwardly and rearwardly by the aforesaid linkage, on its forward stroke to move the carton out of the carton holder and on its rearward stroke to retract the pusher so as to permit the carton holder to continue from the discharge station C to the loading station for another cycle.

Following discharge of the carton from the carton holder the rotor makes another quarter turn, moving the carton holder to an idle station D where the dust flap folders are returned to their retracted positions which until this time have been held in their operative positions by the aforesaid spring means.

It is, of course, necessary to maintain the dust flap closure plates in their operative positions until the carton is moved outwardly from the carton holder at the discharge station to make sure that the closure flap will be closed on them. Since the closure flap is at the outer side of the carton with respect to the direction of discharge the dust flap closure members are disengaged from the dust flaps by the movement of the carton away from them but hold the dust flaps in position until the closure flap is completely folded down into engagement with them.

At the idle station D (FIGS. 22 and 23) there is a bar 338 mounted at the lower end of a post 340, the upper end of which is fastened to a block 342 which in turn is mounted to the upper end of a piston rod 344 projected from the upper end of cylinder 346 mounted in a vertical position on the table. The cylinder 346 provides for raising the bar 338 into engagement with the roller 112—112 or 112x—112x to elevate them from their depressed positions shown in full lines to their elevated positions as shown in dotted lines to restore the closure plates to their inoperative positions. A rod 350 is connected at its upper end to the block 342, extends downwardly therefrom through a guide plate 352 which prevents the bar from rotating about the axis of the rod 344 and is connected at its lower end to a switch 354. The switch 354 operates a timing device so that in the event that for some reason the cylinder 346 does not lower the bar 338 after the closure members have been moved to their inoperative position the rotor will not be indexed. If the bar is lowered the rotor is indexed through a quarter turn to return the carton holder to the loading position. As previously related, there are four such carton holders so that there is always a carton holder at loading position; a carton holder at the vibrating position; a carton holder at the discharge position; and a carton holder at the idle position.

The drive for the apparatus, referring to FIGS. 2 and 25, comprises a motor M, a reduction unit R, a train of gears G and the drive shaft 220. The shaft 26 on which the rotor is mounted is indexed by indexing mechanism I which in turn is driven by suitable linkage from the shaft 220 and the means for lowering and raising the

support 188, lowering and raising the hold-down members 254—254, moving the pusher 307 outwardly and inwardly and raising and lowering the bars 280 and 338 are all driven by suitable cams and linkages from the shaft 220.

It should be understood that the present disclosure is for the purpose of illustration only and that this invention includes all modifications and equivalents falling within the scope of the appended claims.

I claim:

1. In an apparatus for filling a carton closed at one end and open at the other, with packets and closing the open end, the carton being of the kind having at least one closure member hinged to the open end thereof for folding across said open end to close the same, a carton holder supported for movement from a carton receiving position angularly in a vertical plane about a horizontal axis to an upright position for moving a carton received thereby to said upright position with its open end uppermost and with the closure member extended, the carton holder embodying an extention beyond the open top of the carton supported therein capable of supporting a number of packets above the open top of the carton in excess of the volumetric capacity of the carton, means for vibrating the carton in the carton holder to reduce the thickness of the packets to a dimension not exceeding the depth of the carton and means thereafter for folding the closure member over the top.

2. Apparatus for filling a carton open at one end with packets and closing the carton, said carton being of the kind having at least one closure member hinged to the open end thereof for folding across the end, a support to which packets are delivered in a column, a carton holder at said support, said carton holder having an open end, means supporting the carton holder with its open end uppermost for movement from said upright position to a prone position, such that the open end is adjacent the column of packets on the support, said carton holder being constructed and arranged to be engaged with a carton resting on the support when moved to said prone position and when raised to said upright position to lift the carton from the support to an upright position, said carton holder in said prone position being adapted to guide a column of packets into the carton, the length of which exceeds the depth of the carton, and in said upright position to support the stack within the carton with the excess packets above the top, means for vibrating the carton while held in said upright position, and means for folding the closure member across the open top following reduction of the height of the stack to a dimension not exceeding the depth of the carton.

3. Apparatus for filling a carton open at one end with packets and closing the carton, said carton being of the kind having at least one closure member at the open end foldable across the open end, a support to which packets are delivered in a column, said support being adapted to support a carton on one side with its open end confronting the column and with its closure member distended, a carton holder constructed and arranged to be engaged with the prone carton and having open lower and upper ends, means supporting the carton holder for movement from an upright position to a prone position in engagement with the prone carton, means on the carton holder adapted to grip the carton when the carton holder is lowered to said position of

engagement therewith and to raise the carton with the carton holder when the latter is raised to said upright position, said carton holder in said prone position being constructed and arranged to provide an extension at the open end of the carton for guiding a column of packets into the carton, the length of which exceeds the depth of the carton, and in said upright position being adapted to support the stack of packets with the excess packets above the open top, means engageable with the bottom of the carton through the lower open end of the carton holder for vibrating the carton, and means for folding the closure member across the open top following reduction of the height of the stack to a dimension not exceeding the depth of the carton.

4. In an apparatus for filling a carton open at one end with packets and closing the carton, said carton being of the kind having at least one closure member hinged to the open end thereof for folding across said end to close the same, a movable support, a carton holder on the movable support, a plurality of spaced operating stations at which operations are performed in succession which contribute to filling and closing the carton, and means for effecting intermittent movement of the movable support and hence the carton holder from station to station; a first station, a stationary support at said first station to which packets are delivered, said carton holder at said first station being adapted to receive and support a carton in an upright position with its uppermost end open with the closure member distended therefrom and with a stack of packets therein comprised of a predetermined number of packets, the collective thickness of which exceeds the depth of the carton with the excess packets above the open end, a second station, means at the second station operable to reduce the collective thickness of the packets in the stack to a dimension not exceeding the depth of the carton, a third station, and means at the third station operable to discharge the filled carton and simultaneously close the closure member over the open end of the carton.

5. In an apparatus for filling a carton open at one end with packets and closing the carton, said carton being of the kind having dust flaps and a closure flap at said end, a movable support, a carton holder on the movable support, a plurality of spaced operating stations at which operations are performed in succession which contribute to filling and closing the carton, and means for effecting intermittent movement of the movable support and hence the carton holder from station to station; a first station, a stationary support at said first station to which packets are delivered, said carton holder when at said first station being adapted to receive and support a carton in an upright position with its upper end open and with a stack of packets therein comprised of a predetermined number of packets, the collective thickness of which exceeds the depth of the carton with the excess packets above the open end, a second station, means at the second station operable to reduce the collective thickness of the packets in the stack to a dimension not exceeding the depth of the carton and partly close the open end of the carton, a third station, and means at the third station operable to discharge the filled carton and simultaneously completely close the carton.

6. Apparatus according to claim 5, wherein the carton holder embodies a portion which provides an ex-

tension at the open end of the carton corresponding to the cross-section of the interior of the carton.

7. Apparatus according to claim 5, wherein the stationary support is arranged to support a carton on its side with its open end in a position adjacent the place of delivery of the packets thereto, wherein the carton holder is movable on the movable support from an upright position to a prone position over the carton resting on the stationary support, said carton holder including a portion extending beyond the open end of the carton toward the place of delivery through which packets are adapted to be slid into the carton, said portion being of a length such as to accommodate said excess packets, and wherein the carton holder is movable from said prone position, following introduction of a predetermined number of packets into the carton, to an upright position for movement from said first station to the second station.

8. Apparatus according to claim 5, wherein the stationary support is arranged to support a carton on its side with its open end in a position adjacent the place of delivery of the packets thereto, means supporting the carton holder on the movable support for movement from an upright position to a prone position over the carton resting on the stationary support, said carton holder embodying means comprising a part which forms an extension of the interior of the carton at the open end thereof when lowered over the carton through which packets are adapted to be pushed into the open end of the carton and which is of sufficient length to accommodate the excess packets, said carton holder being movable to its upright position following introduction of packets into the carton for movement from said first station to the second station, and means on the carton holder operable by movement of the carton holder over the carton to latch the carton thereto for movement of the carton from the stationary support to an upright position with the carton holder when the latter is moved to its upright position.

9. Apparatus according to claim 8, wherein said last means comprises spaced latch members on the carton holder engageable with the carton by movement of the carton holder to said prone position, said latch members being operable to releasably retain the carton in the carton holder.

10. Apparatus according to claim 7, wherein the portion of the carton holder comprising the extension operates to hold the closure flap and the dust flaps at the open end of the carton distended.

11. Apparatus according to claim 7, wherein the part of the carton holder comprising the extension embodies rectangularly arranged wall members corresponding in arrangement to the sides of the carton, one of which is movable into engagement with the stationary support by movement of the carton holder to said prone position and in said position holds the closure flap distended, and others of which are adapted to hold the dust flaps distended.

12. Apparatus according to claim 11, wherein said one wall member is operable as it is moved downwardly into engagement with the stationary support to spread the dust flaps laterally to admit said other wall members therebetween.

13. Apparatus according to claim 11, wherein said one wall member provides a bridge across the distal end of the closure flap across which the packets are adapted to be pushed into the carton.

14. Apparatus according to claim 7, wherein the packets are delivered to the stationary support in two columns, wherein the part comprising the extension embodies rectangularly arranged wall members, bottom, top and side walls, wherein the bottom wall is adapted to be disposed in engagement with the stationary support when the carton holder is moved to said prone position to hold the closure flap distended, and guide means on the top wall for guiding packets through the holder into the carton in two columns.

15. Apparatus according to claim 7, wherein the packets are delivered to the stationary support in two columns, wherein the part comprising the extension embodies rectangularly arranged wall members, bottom, top and side walls, and a divider element attached to the inner side of the top wall midway between the side walls and extending downwardly therefrom toward the bottom wall operates to guide the packets through the carton holder into the carton in two columns.

16. Apparatus according to claim 7, wherein the part comprising the extension embodies rectangularly arranged wall members, bottom, top and side walls, wherein the bottom wall is adapted to be disposed in engagement with the stationary support when the carton holder is moved to its prone position to hold the closure flap distended, and elements at the inner side of the top wall projecting downwardly therefrom operable to support packets upright as they are moved through the extension into the carton.

17. Apparatus according to claim 16, wherein said elements comprise bristles.

18. Apparatus according to claim 7, comprises a gauge block on the stationary support with which the bottom of the carton is adapted to be engaged to position the carton thereon for engagement of the carton holder therewith.

19. Apparatus according to claim 7, comprising a track extending from station to station with which the bottom of the carton is adapted to be engaged while supported within the carton holder and along which the carton slides as it is moved from station to station by the carton holder.

20. Apparatus according to claim 7, comprising a latch on the movable support for releasably holding the carton holder in said upright position.

21. In an apparatus for filling a carton open at one end with packets and closing the carton, said carton being of the kind having dust flaps and a closure flap at the open end, a movable support, a carton holder on the movable support, a plurality of spaced operating stations at which operations are performed in succession which contribute to filling and closing the carton, means for effecting movement of the movable support and hence the carton holder from station to station, a first station, a stationary support at said first station to which packets are delivered, said carton holder when at said first station being adapted to receive and support a carton in an upright position with the upper end open and with a stack of packets therein comprising a predetermined number of packets, the collective thickness of which exceeds the depth of the carton with the excess packets above the open end, a second station, vibrator means at the second station operable by shaking the stacked packets to reduce the collective thickness of the packets to a dimension not exceeding the depth of the carton, means at said second station operable to close the dust flaps over the open end of the car-

ton, a third station, and means at the third station for discharging the filled carton and closing the closure flap.

22. Apparatus according to claim 21, comprising a track extending from station to station on which the bottom of the carton is supported by the carton holder and along which it is moved by the movable support, said track containing a gap at said second station, an elevator situated in said gap at a level such as to receive the bottom of the carton as it is moved to said second station, a vibrator at said second station and means for lowering the elevator and the carton resting thereon into engagement with the vibrator.

23. Apparatus according to claim 22, wherein said last means is operable to raise the elevator and carton to the level of the track following vibration.

24. Apparatus according to claim 21, wherein the vibrator comprises a cantilever supported spring member and a rotary cam engaged with said spring member operable by rotation to effect vibration of the spring member.

25. Apparatus according to claim 7, comprising pressure-applying means at said second station supported in a position above the path of travel of the carton holder such as to allow the carton holder to move beneath it, and means for lowering said pressure-applying means into engagement with the top of the stack of packets while effecting vibration of the stack.

26. Apparatus according to claim 21, wherein two stacks of packets are supported in the carton, comprising pressure-applying means at said second station supported in a position above the path of travel of the carton holder such as to allow the carton holder to move beneath it, means for effecting vertical movement of the pressure-applying means, said means including two pressure-applying plates for engagement with the tops of the two stacks, and means for lowering the pressure-applying means into engagement with the stacks while effecting vibration and for raising said pressure-applying means from the stacks following vibration.

27. Apparatus according to claim 21, wherein the carton holder embodies means for folding the dust flaps inwardly over the top opening, and wherein there is means at the second station operable following settling of the packets into the carton to cause said means to fold said dust flaps across the open top.

28. Apparatus according to claim 21, comprising folding means for folding the dust flaps inwardly over the open top, means for moving said folding means from an inoperative to an operative position to fold the dust flaps over the top, and means for holding said folding means in said operative position as the carton holder moves from the second station to the third station.

29. Apparatus according to claim 21, wherein the carton holder embodies pivotally supported closure members supported for pivotal movement toward each other and openings through which the closure members are adapted to be moved inwardly from inoperative positions to operative positions to bend the dust flaps inwardly over the open top, means on the carton holder yieldingly holding said closure members in their inoperative positions, and means at said second station operable following vibration such as to reduce the height of the stack to a dimension no greater than the depth of the carton to rotate the closure members to said operative positions.

30. Apparatus according to claim 29, wherein said means which holds the closure members in their inoperative positions operates when the latter are moved to their operative positions to hold them in said operative positions while the movable member is moving the carton holder to the third station.

31. Apparatus according to claim 30, wherein spring means yieldably holds the closure members in each of their positions.

10 32. In an apparatus for filling a carton open at one end with packets and closing the carton, said carton being of the type having dust flaps and a closure flap at the open end, a movable support, a carton holder on the movable support, a plurality of spaced stations at 15 which operations are performed in succession which contribute to filling and closing the carton, means for effecting movement of the movable support and hence the carton holder from station to station, a first station, a stationary support at said first station to which packets are delivered, said carton holder at said first station being adapted to receive and support a carton in an upright position with its upper end open and with a stack of packets therein comprised of a predetermined number of packets, the collective thickness of which exceeds the depth of the carton with the excess packets above the open end, a second station, means at said second station for condensing the packets within the open carton and closing the dust flaps, a third station, a ram at the third station, means for effecting movement of the ram to push the carton from the carton holder, and folding means disposed in position such as to fold the closure flap downwardly against the dust flaps as the carton is expelled.

33. Apparatus according to claim 32, comprising spaced guide members supported at the third station, said ram being mounted in a position to engage the carton at said third station and push it from the carton holder between the guide members to a position of discharge, and a folding blade mounted between the guide members at a level corresponding to the top of the carton operable as the carton is expelled from the carton holder and moved therebetween to intercept and fold the closure flap against the top.

34. Apparatus according to claim 33, wherein said folding blade is adjustable heightwise.

35. Apparatus according to claim 32, comprising means for effecting reciprocation of the ram.

36. Apparatus according to claim 32, comprising a conveyor situated at the outer end of the guide members onto which the carton is pushed by the ram.

37. In an apparatus for filling a carton open at one end with packets and closing the carton, said carton being of the kind having dust flaps and a closure flap at the open end, a rotatable support, a plurality of carton holders mounted on the support at equal angular distances from each other, a plurality of equally spaced stations arranged about the axis of rotation of the rotatable support such that the work holders are movable intermittently from station to station and at any interval of rest there is a carton holder at each station, and means for effecting intermittent rotation of the rotor; a first station, a stationary support at the first station onto which packets are delivered, means mounting the carton holders on the rotor for movement to a position on the stationary support into engagement with a carton resting thereon, said carton holder while in said position being adapted to guide packets into the carton,

said carton holder being thereafter movable to an upright position, a second station, vibrator means at the second station operable while the carton holder with the carton supported thereby is at said second station to shake the packets until the stack of packets settle into the carton, closure members on the carton holder movable from inoperative to operative positions to fold the dust flaps against the open top following settling of the packets into the carton, means at the second station for moving the closure member to their inoperative positions, means on the carton holder for maintaining the closure members in said operative positions, a third station, a ram at the third station operable to expel the carton from the carton holder, closure means at said third station for folding the closure flap against the dust flaps as the carton is expelled, a fourth station, and means at the fourth station operable to restore the closure members on said carton holder to their inoperative positions.

38. Apparatus according to claim 37, wherein the carton holder is open at its lower end and there is a rail concentric with the axis of rotation of the rotor on which the bottom of the carton is adapted to rest and on which it slides from station to station as the rotor moves the carton holder from station to station.

39. Apparatus according to claim 37, wherein a releasable latch member holds each carton holder in upright position as it travels from the first station through the several stations and back to the first station, said latch member being manually releasable to permit rotating the carton holder downwardly into engagement with a carton resting on the stationary support at said first station.

40. The method of packaging envelope like packets in a carton of predetermined depth closed at one end and open at the other with at least one closure member at open end, comprising filling the carton with the envelope like packets, supporting a number of additional packets above the packets confined in the carton in vertical alignment therewith and resting on the packets within the carton to form a column of packets the height of which exceeds the depth of the carton, vibrating the carton and column of packets contained therein to effect the redistribution of the material in the packets to uniform thickness such that the height of the column of packets is not greater than the depth of the carton and then closing the end closures over the open end of the carton.

41. The method of packaging envelope-like packets containing material which has settled to the lower part of the packets as a consequence of handling operations preparatory to packaging, such that the lower portions are substantially thicker than the upper portions, comprising supporting a carton of a predetermined depth on its side with one end open, placing a holder about the open end of the carton such as to increase the effective depth of the carton, sliding a group of packets, the collective thickness of the thicker portions of which is greater than the depth of the carton but less than the depth of the carton plus the length of the holder into the holder and carton, tilting the holder and carton to an upright position, and vibrating the carton to effect

redistribution of the material in the packets to a uniform thickness such that the collective thickness of the uniformly thick packets is no greater than the depth of the carton.

42. The method of packaging envelope-like packets containing material which has settled to the lower portions of the packets as a consequence of handling prior to packaging so that the lower portions of the packets are much thicker than the upper portions thereof, comprising supporting a carton of predetermined depth on its side with one open end, supporting a holder at the open end of the carton, gathering a plurality of such packets, the collective thickness of the thicker portions of which is greater than the depth of the carton but less than the composite depth of the carton and holder, piloting the packets through the holder and open end of the carton into the carton, tilting the carton and holder to an upright position, vibrating the bottom of the carton to effect redistribution of the material in the packets to a uniform thickness such that the collective thickness of the uniformly thick packets is less than the depth of the carton and removing the holder.

43. A method according to claim 42, comprising arranging the packets on a pilot and moving the pilot and packets through the holder into the carton.

44. A method according to claim 44, comprising supporting the thinner portions of the packets in the stack in spaced parallel relation at a spacing corresponding substantially to the thickness of the thicker portions of the packets.

45. The method of packaging envelope-like packets containing material which has settled to the lower portions of the packets as a consequence of handling prior to packaging so that the lower portions of the packets are substantially thicker than the upper portions thereof, comprising supporting a carton of predetermined depth on its side, with one end open, supporting a holder about the open end, selecting a plurality of packets arranged in two columns side by side, the collective thickness of the thicker portions of the packets in each column exceeding the depth of the carton but being less than the composite depth of the carton and holder, piloting the leading packets in the columns through the holder into the carton so as to dispose the packets in separately defined columns, tilting the carton and holder to an upright position and while holding the columns in divided vertical stacks vibrating the carton to effect redistribution of the material in the packets to a uniform thickness such that the composite thickness of the uniformly thick packets in each stack is less than the depth of the carton.

46. A method according to claim 45, comprising supporting the packets at the leading ends of the columns in upright positions and manually pushing the rearmost packets of the selected numbers of packets forwardly against the preceding packets in the columns to slide the columns through the holder into the carton.

47. A method according to claim 41, comprising applying pressure to the upper end of the stack of packets while effecting vibration thereof.
